STEREOSCOPIC SLIDE VIEWER

Thomas W. Kellogg, Duarte, Calif., assignor to Sawyer's Inc., Progress, Oreg., a corporation of Oregon

Application May 26, 1958, Serial No. 51,086

Term of patent 14 years

(Cl. D57—7)

Fig. 1 is a front elevation of a stereoscopic slide viewer showing my new design;

Fig. 2 is a top plan view of the viewer;

Fig. 3 is a rear elevation;

Fig. 4 is a side elevation thereof; and

Fig. 5 is a partial, horizontal section on an enlarged scale taken substantially along line 5—5 of Fig. 2.

The bottom surfaces of the viewer are substantially plain.

I claim:

The ornamental design for a stereoscopic slide viewer, as shown and described.
